GAS IGNITER

Joseph A. Cerny, University Heights, and Julius Converse, East Cleveland, Ohio, assignors to The Bryant Heater Company, Cleveland, Ohio, a corporation of Ohio

Application June 17, 1941, Serial No. 398,434

2 Claims. (Cl. 219—32)

This invention relates to improvements in gas igniters, and has reference particularly to the mounting of an igniter of the heating coil type, and to means for assuring the presentation thereof to a highly combustible gas and air mixture.

One of the objects of the invention is the provision of improved means for mounting of the coil in its insulation block which at the same time shall provide improved electrical connections with the lead wires.

Another object is the provision of improved means for mounting the insulation block.

A further object is the provision of improved means for causing deceleration and turbulence of the combustible gas stream, and its mixture with additional air just prior to contacting the heating coil.

Other objects and features of novelty will appear as we proceed with the description of those embodiments of the invention which, for the purposes of the present application, we have illustrated in the accompanying drawing, in which

Fig. 1 is a plan view partially in section and on an enlarged scale of a coil block with coil and lead wires assembled therein in accordance with the invention.

Fig. 2 is an end view of the same.

Figs. 3 and 4 are front and rear views respectively.

Fig. 5 is a fragmental elevational view showing means for mounting the coil on an upright pilot tube.

Fig. 6 is an elevational view of the same at right angles to that of Fig. 5.

Fig. 7 is a cross-sectional view taken substantially on the line 7—7 of Fig. 5.

Fig. 8 is a plan view of a modified form of mounting suitable for a horizontally extending pilot tube.

Fig. 9 is a cross-sectional view taken substantially on the line 9—9 of Fig. 8.

Fig. 10 is a fragmental plan view of another type of mounting suitable for horizontally arranged pilot tubes.

Fig. 11 is a side elevational view of the same, and

Fig. 12 is a cross-sectional view taken substantially on the line 12—12 of Fig. 10.

In the drawing the coil block is illustrated at 10. It is formed of suitable heat resistant electrical insulation, for example, porcelain or lava. The front side of the block is provided with a pair of longitudinally extending wings 11, 11 forming a channel therebetween. The ends of these wings stop somewhat short of the ends of the block 55

proper, as clearly illustrated in Figs. 1 and 3. An electric heating coil 12 is positioned within this channel, the two end wires 13 and 14 of the coil projecting through small passages 15 and 16 in the block, which passages communicate respectively with cavities 17 and 18 each of which is open through at least one wall of the block in order that the cavities may be accessible from the exterior of the block. As shown herein the cavity 17 is open through the rear wall and the bottom wall of the block, while the cavity 18 is open through the rear wall and top wall of the block.

The block is also provided with longitudinal passages 19 and 20 of larger bore than the passages 15 and 16, for the reception of lead wires 21 and 22. These wires project through the passages into the cavities 17 and 18, thereby intersecting the coil end wires 13 and 14. Each pair of intersecting wires is joined mechanically and electrically in some suitable manner, preferably by means of a high temperature solder, the soldered joints being illustrated in the drawing at 23 and 24 respectively. A brazed connection and a welded connection are obviously mechanical equivalents of the soldered joint and should be understood as comprehended by the term soldered joint. The cavities are of such size that a soldering tool of appropriate dimensions may be readily inserted, and when the joint is made, whether soldered or otherwise, a good mechanical connection as well as a good electrical connection is accomplished and the wires are firmly held in the block, and each one locks the other in place.

Referring to Figs. 5, 6 and 7, the coil block is shown mounted upon an upright pilot tube 25 having a lower port 26, upper ports 27 and a series of intermediate ports 28 for transmitting flame from the lower port 26 to the upper ports 27. A bracket 29 having a shelf member 30 is fastened to the tube 25 by a screw 31 or the like in such position that the shelf 30 stands adjacent to and beneath the port 26. The block 10 is mounted upon this shelf member by means of a screw 32 which extends through a smooth cylindrical hole 33 in the block into a threaded hole in the bracket.

A mixture of combustible gas and air, herein-after called gas, when discharged from port 26, flows over shelf 30 and up against an end wall of the block 10, which then constitutes a target for the gas stream. Upon striking the target the gas rebounds, is deflected and rolls sidewise in both directions as well as upward, setting up low turbulence and effecting a mixture with additional air. The term target as hereinafter employed should be understood as applying only to an ele-

ment having the functions just described, and as excluding a mere gas deflector. The shelf or guard plate 30 prevents air currents from disturbing the gas stream. A small portion of this mixture after moving sidewise enters the adjacent 5 end of the coil 12 and envelopes its exterior so that ignition of the lean mixture takes place readily when the coil attains combustion temperature.

Referring to Figs. 8 and 9, 35 is a horizontal pilot tube having a port 36. 37 is a relatively fixed element upon which the lighter coil and associated parts are carried. A sheet metal stamping comprising portions 38 and 39 at right angles to each other extends beneath the fixed element 37 and has an upwardly extending rear flange 40 engaging one edge of the element 37. The front side 39 of this stamping is cut away to receive the two wings 11 of the block and the space therebetween in which the coil 12 is located. A bottom portion 41 of the stamping extends forwardly beneath the coil and beneath the port 36 of the pilot tube. This stamping and the block 10 are held in place by a bolt 42 and nut 43, the bolt extending through a hole in part 37, through a slot 44 in part 38 of the stamping and through the hole 33 in the block. The part 37 is broken away in Fig. 8 of the drawing in order to more clearly illustrate the stamping. It will be observed that by making the cut-away portion of the front wall 39 fit closely around the wings 11 the block and stamping are interconnected so that relative displacement is impossible so long as the bolt 42 and its nut 43 remain in position.

In this form of the invention the front wall 39 of the stamping opposite to the port 36 constitutes the target for the gas stream. Some of the gas may strike the bottom portion 41 of the stamping before it encounters the target proper, but the effect is quite similar to that obtaining with the use of the construction shown in Figs. 5, 6 and 7; that is to say, the gas after it strikes the wall 39 is deflected, becomes mixed with air, and rolls in opposite directions from the target, part of it entering the coil 12. The bottom portion 41 of the stamping in this case functions partly as a guard plate or shelf for preventing currents of air from interfering with the flow of the gas stream and partly as a deflector for directing the oblique gas stream against the target.

In Figs. 10, 11 and 12 a horizontal pilot tube 45 lies directly adjacent a supporting element 46 upon which the block 10 is mounted by means of a screw 32. In this modification the target is constituted by a flange 47 extending upwardly from a sheet metal element 48 which runs beneath the supporting element 46 and is secured thereto by a screw 49. This sheet metal element may have a reinforcing flange 50 and may have further an integral cap member 51 for closing the end of the pilot tube 45. In the tube there is a port 52 positioned opposite the target 47. Here the flat upper surface of the supporting element 46 constitutes the guard plate or shelf and the gas stream flows above it toward the target, then breaking up, mixing with air, and a portion entering the end of the heating coil 12.

While in all of the coil mountings herein illustrated the guard plate is shown as a flat horizontal shelf, it is not essential that it be flat or horizontal and, in fact, we have found that a vertical plate functions quite satisfactorily in some instances. It should, however, be close

enough to the gas stream to guard the stream in order that the latter may flow undisturbed. During this flow the stream expands and decelerates and picks up air. The presence of the guard permits the use of a relatively long gas stream which of course increases the opportunity for expansion and deceleration. When the decelerated stream strikes the target it is deflected in all directions and may be said to roll into a cloud of low turbulence which moves radially outward at a relatively slow rate of speed, picking up additional air in the process, so that the mixture becomes leaner and leaner as it progresses outward from the point of impact upon the target. An almost quiescent condition of the correct mixture at the point of ignition is desirable. It is not well to so restrict the pilot port that the latter can easily clog. Therefore, since a stream of substantial size must be employed, a remote target location is desirable. The more remote this location, the more necessary becomes the guard. The igniting coil is arranged preferably with its axis in a generally radial direction with respect to this point, with the result that at some part of its length an ideal mixture, that is one capable of substantially complete combustion, is contacted. The ignition of the mixture is certain to occur at this point at least. The rate of flow at the coil is also low so that the cooling effect due to flow is minimized.

Gas in different localities differs considerably in its composition, so that the point of substantially perfect combustion mixture may be at one radial distance from the center of the cloud for one locality and at an entirely different distance for another locality, but by arranging the coil with its axis in a generally radial direction the apparatus automatically compensates for such different gases and functions properly in a wide variety of cases without any shifting of coil position.

Having thus described our invention, we claim:

1. In a gas igniter, a heat resistant block of electrical insulation, an electric igniter coil mounted thereon, said block having a passage therethrough into which one end of said coil projects and having a second passage substantially intersecting said first passage, a lead wire in said second passage, said block having an open cavity at the intersection of said passages providing access for a soldering tool, the crossed wires extending adjacent a wall of said cavity, whereby the said wall forms a back stop for the wires when the tool is pressed against them to effect a soldered joint.

2. In a gas igniter, a heat resistant block of electrical insulation, an electric igniter coil carried upon the face of the block with straight wires at its ends projecting into the block through passages provided therein, by which the wires are located, said block having other passages spaced apart in a plane parallel to the face of the block, an electric conductor having lead wires straight end portions of which extend through and are located by said last-named passages, said block having open cavities extending thereto from the back of the block and from the opposite sides thereof, each coil end wire meeting one lead wire in one of said cavities, and a soldered joint between each coil end and the corresponding lead wire in each of said cavities.
